UNITED STATES PATENT OFFICE

2,515,767

BEVERAGE COOLER

Murray M. Fibus, Youngstown, Ohio

Application November 29, 1946, Serial No. 713,142

2 Claims. (Cl. 62—141)

1

This invention relates to a beverage cooler and more particularly to a device wherein mechanical refrigeration is employed for cooling beverages, and wherein the beverage being cooled is deposited in an appropriately shaped evaporator of a mechanical refrigeration system.

The principal object of the invention is the provision of a beverage cooler comprising a mechanical refrigerator evaporator forming a liquid receptacle for a beverage to be cooled.

A further object of the invention is the provision of a beverage cooler comprising an insulated cabinet having a double walled inner container therein and said inner container having partitions therein and the said double walled inner container adapted to serve as the evaporator of a mechanical refrigeration system.

A still further object of the invention is the provision of a beverage cooler including a cabinet and a container therein, the said container having a plurality of partitions therein dividing the same into a plurality of liquid holding compartments.

The beverage cooler shown and described herein is particularly adapted for chilling fruit juices and other liquids commonly served as beverages and is of a size and shape facilitating its placement on the back bar or counter of a tavern or restaurant and adapted to be connected to a mechanical refrigerating system including a compressor and in alternate form including a compressor as an integral unit thereof.

The particular novelty in the disclosed device is believed to reside in the formation of the liquid receiving compartments in the inner container thereof and in the formation of this inner container as an evaporator of a mechanical refrigeration system.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a front view of the beverage cooler with parts broken away and parts in cross section.

Figure 2 is a top view of the beverage cooler with parts broken away and parts in cross section.

Figure 3 is a top view of a modified form of the beverage cooler with parts broken away and parts in cross section and showing a refrigeration compressor in connection therewith.

By referring to the drawings and Figures 1 and 2 in particular it will be seen that a beverage cooler has been disclosed which consists of a cabinet 10 having a top 11 and enclosing an inner container 12 spaced with respect to the bottom, side and end walls of the cabinet 10 by means of insulation 13. The inner container 12 is subdivided into a plurality of compartments by means of partitions 14 which are positioned transversely thereof. Each of the compartments formed by the partitions 14 in the container 12 is adapted to receive liquid to be chilled and in order that liquid may be conveniently introduced thereto openings 15 are formed in the top 11 in registry with each of the compartments 16 formed by the partitions 14 in the container 12. Resilient gaskets 16 are positioned in each of the openings 15 which are thereby adapted for the satisfactory reception of inverted bottles or jugs 17. For example, one of the compartments in the container 12 may be of a size to hold a gallon of beverage and a second gallon of beverage in the jug 17 may then be placed in inverted position in registry with the gasket 16.

As the liquid contents are removed from the compartment in the container 12, the beverage in the jug 17 will flow into the compartment. This provides for the visual indication of the amount of the beverage in the compartment and at the same time readily discloses what kind of beverage is being dispensed from each compartment. In order that the beverage in the compartments in the container 12 may be conveniently withdrawn, spigots 18 are provided each of which communicates with the adjacent compartment in the container 12, as best shown in Figure 2 of the drawings.

Still referring to Figures 1 and 2 of the drawings it will be observed that the side and end walls of the container 12 are of double thickness, the exterior wall thereof being indicated by the numeral 19 and being preferably corrugated so as to form a plurality of channels 20 about the inner wall of the container 12. The corrugations engage the said inner wall to form a plurality of parallel paths for the flow of a refrigerant. The channels 20 are separated by a vertical partition 32' extending the full height of the wall 19. Tubular connections 21 are provided and establish communication with the channels which surround the container 12 so that a refrigerant may be directed thereto through

one of the tubular conduits 21 where it flows through the double walled container 12 and back to the compressor through the other one of the conduits 21. The double walled container thereby serves as an evaporator in a mechanical refrigeration system.

It will be obvious to those skilled in the art that if desired the same double walled construction may be followed in forming the bottom of the container 12 in addition to the side and end portions thereof if the added cooling effect is desired.

It will thus be seen that a simple and efficient beverage cooler has been disclosed which is of relatively compact design and capable of efficient operation in cooling beverages and providing for dispensing the same in that it forms an integral part of a mechanical refrigeration system and is thereby capable of most effectively refrigerating the beverage placed therein. It will be obvious to those skilled in the art that the necessary expansion valve, condenser and compressor are needed to form the operating mechanical refrigerating systems in connection with the evaporator forming an integral portion of the beverage cooler as shown in Figures 1 and 2 of the drawings. As these parts are well known in the art, they are not illustrated herein or further described.

The invention may be modified if desired by shortening the cabinet or increasing its length and including a compressor in an end compartment in order to form a completely self-containing unit. By referring to Figure 3 of the drawings such modified beverage cooler may be seen to comprise an outer cabinet 22 and an inner container 23 spaced with respect to the bottom, side and end walls of the outer cabinet 22 by means of insulation 24. The inner container 23 has double walled construction, the outer wall being indicated by the numeral 25 and preferably corrugated to form a plurality of channels surrounding the container 23 so that an effective evaporator of a mechanical refrigeration system is formed thereby. Tubular connections 27 communicate with the channels 26 and with a compressor and condenser unit 28 which is disposed in a compartment 29 in one end of the outer cabinet 22. The cabinet 22 is also provided with a top 30 and a plurality of spigots 31 each of which communicates with its adjacent compartment in the container 23. In the same manner as the construction heretofore described and

illustrated in Figures 1 and 2 of the drawings. The top 30 of the device is provided with openings 31 and gaskets 32 thereabout and adapted to receive jugs indicated by the numeral 33.

It will thus be seen that a simple and efficient beverage cooler has been disclosed which may be formed in either one of two styles, one style of which is connected for operation to a remotely located mechanical refrigeration system and the other style of which incorporates the complete refrigeration system therein. In both forms of the invention the evaporator portion of the refrigerating system forms the beverage container and is preferably but not necessarily subdivided into a plurality of compartments into which various beverages may be introduced for cooling.

Having thus described my invention, what I claim is:

1. In a beverage cooler a container, means for withdrawing a beverage from the container, means cooperative with the outer surface of the container to provide a fluid circulating passage, said means comprising a horizontally corrugated panel sealed at its upper and lower edges to the side walls of the said container, a vertical partition between said corrugated panel and said container and inlet and outlet orifices in said corrugated panel one on each side of the said vertical partition whereby a refrigerant may be introduced into the said area between the horizontally corrugated panel and the said container for cooling the contents of the said container.

2. The beverage cooler defined in claim 1 and further characterized by the positioning of a plurality of transverse partitions in the said container.

MURRAY M. FIBUS.
